The ornamental design for an applicator tray for a buttress applicator for a surgical stapler, as shown and described.

DESCRIPTION

FIG. 1 is a top perspective view of an embodiment of an applicator tray for a buttress applicator for a surgical stapler, showing our new design;

FIG. 2 is a top perspective view of the applicator tray of FIG. 1, shown without a desiccant paperboard and without the buttress applicator;

FIG. 3 is a top plan view of the applicator tray of FIG. 2; FIG. 4 is a bottom plan view of the applicator tray of FIG. 2;

FIG. 5 is a side elevational view of the applicator tray of FIG. 2, the opposite side elevational view being a mirror image thereof;

FIG. 6 is a rear elevational view of the applicator tray of FIG. 2;

FIG. 7 is a front elevational view of the applicator tray of FIG. 2;

FIG. 8 is a cross sectional view of the applicator tray of FIG. 2, taken along line 8-8 of FIG. 3;

FIG. 9 is a cross sectional view of the applicator tray of FIG. 2, taken along line 9-9 of FIG. 3;

FIG. 10 is a top perspective view of the applicator tray of FIG. 1, shown with a flap thereof rotated to an open position;

FIG. 11 is a top perspective view of the applicator tray of FIG. 2, shown with the flap rotated to an open position;

FIG. 12 is a top plan view of the applicator tray of FIG. 11; FIG. 13 is a bottom plan view of the applicator tray of FIG. 11;

FIG. 14 is a side elevational view of the applicator tray of FIG. 11, the opposite side elevational view being a mirror image thereof;

FIG. 15 is a rear elevational view of the applicator tray of FIG. 11;

FIG. 16 is a front elevational view of the applicator tray of FIG. 11;

(Continued)

FIG. 17 is a cross sectional view of the applicator tray of FIG. 11, taken along line 17-17 of FIG. 12;
FIG. 18 is a cross sectional view of the applicator tray of FIG. 11, taken along line 18-18 of FIG. 12;
FIG. 19 is a top perspective view of another embodiment of an applicator tray for a buttress applicator for a surgical stapler, showing our new design;
FIG. 20 is a top perspective view of the applicator tray of FIG. 19, shown without a desiccant paperboard and without the buttress applicator;
FIG. 21 is a top plan view of the applicator tray of FIG. 20;
FIG. 22 is a bottom plan view of the applicator tray of FIG. 20;
FIG. 23 is a side elevational view of the applicator tray of FIG. 20, the opposite side elevational view being a mirror image thereof;
FIG. 24 is a rear elevational view of the applicator tray of FIG. 20;
FIG. 25 is a front elevational view of the applicator tray of FIG. 20;
FIG. 26 is a cross sectional view of the applicator tray of FIG. 20, taken along line 26-26 of FIG. 21;
FIG. 27 is a cross sectional view of the applicator tray of FIG. 20, taken along line 27-27 of FIG. 21;
FIG. 28 is a top perspective view of the applicator tray of FIG. 19, shown with a flap thereof rotated to an open position;
FIG. 29 is a top perspective view of the applicator tray of FIG. 20, shown with the flap rotated to an open position;
FIG. 30 is a top plan view of the applicator tray of FIG. 29;
FIG. 31 is a bottom plan view of the applicator tray of FIG. 29;
FIG. 32 is a side elevational view of the applicator tray of FIG. 29, the opposite side elevational view being a mirror image thereof;

FIG. 33 is a rear elevational view of the applicator tray of FIG. 29;
FIG. 34 is a front elevational view of the applicator tray of FIG. 29;
FIG. 35 is a cross sectional view of the applicator tray of FIG. 29, taken along line 35-35 of FIG. 30; and,
FIG. 36 is a cross sectional view of the applicator tray of FIG. 29, taken along line 36-36 of FIG. 30.
The evenly-spaced broken lines in the drawings are included for purpose of illustrating portions of the applicator tray for a buttress applicator for a surgical stapler that form no part of the claimed design.
